UNITED STATES PATENT OFFICE.

ADELBERT W. GRAY, OF PITTSBURGH, PENNSYLVANIA, ASSIGNOR TO DAVID E. BOWN, OF PITTSBURGH, PENNSYLVANIA.

PUSH-BUTTON SWITCH.

1,126,985.

Specification of Letters Patent.

Patented Feb. 2, 1915.

Application filed April 20, 1912. Serial No. 692,079.

To all whom it may concern:

Be it known that I, ADELBERT W. GRAY, a resident of Pittsburgh, Northside, in the county of Allegheny and State of Pennsylvania, have invented a new and useful Improvement in Push-Button Switches; and I do hereby declare the following to be a full, clear, and exact description thereof.

My invention relates to push button switches, and has special reference to what is known as a single push button switch.

The object of my invention is to provide a cheap, simple and efficient single push button switch, which will enable the switches to be easily and quickly thrown, as well as one which will be strong and durable and will be accurate and positive in its movements of operation.

My invention consists, generally stated, in the novel arrangement, construction and combination of parts, as hereinafter more specifically set forth and described and particularly pointed out in the claims.

To enable others skilled in the art to which my invention appertains to construct and use my improved push button switch, I will describe the same more fully, referring to the accompanying drawings, in which—

Figure 1 is a side view of my improved push button switch in the contacting position and showing the box or casing in section. Fig. 2 is an end view of the same, with the box in section. Fig. 3 is a front view showing the box and frame in cross-section. Fig. 4 is a side view partly in section of the switch showing an intermediate position of the same. Fig. 5 is a like view showing another position of the same when the contact is broken. Fig. 6 is an inverted sectional view of the button showing the device for rotating the button. Fig. 7 is a like view showing another position of the same. Figs. 8 and 9 are face views of the button employed and showing the same in different positions.

Like symbols of reference herein indicate like parts in each of the figures of the drawings.

As illustrated in the drawings, 1 represents the switch box or receptacle, which is formed of any suitable material, and 2 is the rocking shaft located in said receptacle

and fulcrumed in a bracket 3 rigidly fixed to and supported by the usual metal frame 4 through the usual screw connection. This frame 4 is removably secured to the front of the receptacle 1 by means of the screws 5' passing through enlargements 5 on the ends of said receptacle and engaging with said frame, while the usual face-plate 4' is fixed to the front of said receptacle and over said frame in the usual manner by the screws 4'' for bearing against the face of the wall or other place in which the switch is placed for use. Extending around the shaft 2 and centrally of the receptacle 1 is the guide-sash 6, which is preferably stamped from sheet metal, and has the push-button 7 rotatably mounted thereon by a pin 8 on the front end of said sash fitting loosely within a seat for the same in said button. This button 7 extends loosely through an opening 10 in the frame 4 and through a like opening in the face-plate 4' and acts as the outer end guide for the free end thrust of the sash 6. A rim 9 is formed on the inner end of said button to fit within a seat 9' in the back of the frame 4 to hold said button in position. The angular ends 11' on a bracket 11 carried by the rear end of the bracket 3 forming part of the frame 4 are suitably slotted to guide the inner or rear ends of the sash 6.

A pin 12 is rigidly fixed to and projects from each side of the sash 6, which pin is carried with the end travel of said sash, and has one of its projecting ends flattened on its two sides, as at 13, to act as a trigger-finger, as hereinafter described, while the other projecting end is made smaller and of round form, as at 13' to provide a fulcrum for the two-claw gripping device 14, and upon such fulcrum the said device is movably secured by a spring-washer or pin 14', but in such a manner as will enable said device to rock with limited friction. One of the extended ends 15' of the spiral spring 15 is securely fixed to the bracket 11 of the frame 4, as by the screw 16, and its other extended end 15'' is curved, as at 17, in order to adapt its pressure against the pin 12 in such a manner as to flexibly hold the sash 6 normally outward. A cross-arm 18, preferably formed of stamped metal is rigidly mounted on the shaft 2, and a

switch-blade 19 is securely fixed to said arm and electrically insulated therefrom, as well as from said shaft by a suitable insulating material 20. A locking-tumbler 21 is rigidly mounted on the shaft 2 and carries the switch blade 22, which is securely fixed to said tumbler and rocks with the same, and such blade is insulated from said tumbler by a suitable insulating material 23. Two similar spiral springs 24 and 25 are flexibly mounted on the shaft 2, one end of the spring 24 being securely attached to the tumbler 21, as at 24', and in such manner as to rock therewith, while the spring 25 is similarly attached to the cross-arm 18, as at 25', and movable therewith, so that both these springs will tend to move in unison when the said shaft rocks in either direction. The other or free ends 24'' and 25'' of the springs 24 and 25 protrude oppositely to each other through the central open space of the gripping device 14, and one of said ends will always rest immediately behind and directly in the rearward path of either of the claws 26 and 27 on the device 14 and depending upon the direction of tilt of said device. A rounded shifting pin or lug 28 is rigidly carried by the tumbler 21 and normally assumes the positions indicated in Figs. 1 and 5, and said pin always protrudes through the central opening in the device 20, as indicated in Figs. 1 to 5 inclusive.

Assuming that the switch is normally closed, as shown in Figs. 1 to 3 inclusive, the switching operation will ensue by pressing the button 7 to slide the guide-sash 6 inward which will carry the claw 27 of the gripping device 14 into engagement with the projecting free end 24'' on the spring 24, and thereby carry said spring end inward to a distance slightly greater than that represented by one-fourth of the circumference of shaft 2, so that said free end is disposed in respect to said shaft, as shown in Fig. 4, and will thus create a torsion of said spring, which is exerted upon said shaft and tends to draw the switch-blades 19 and 22 from their closed positions, as indicated in Figs. 1 to 3, and throw them into their open positions, as shown in Figs. 4 and 5. This action will not occur until the trigger-finger 12 has traveled inward with the guide-sash 6 to slide said finger out of the locking slot 38 to the position shown in Fig. 4, while the shorter segment 30 of the tumbler 21 will escape from engagement with said pin to permit the torsion of the spring 25 to throw said tumbler into the position shown in Fig. 4, and thus throw the blades 19 and 22 into open position

and free from the respective contact clips 31 and 32, and 33 and 34, as shown in Fig. 4.

At the instant of the opening of the contacts as just described, the push-buttons 7 are held pressed to its inward limit of travel and thereby the finger 12 is momentarily held outward until the throw of the tumbler 21 has caused the stop catch 36 thereon in the position shown in Fig. 4 to recede from said finger to bring the stop catch 35 on said tumbler into engagement with said finger at its position shown in said Fig. 4, and such operation will limit the throw of the blades 19 and 22 to definite one-fourth revolution. In the meantime, the quarter revolution of the tumbler 21 will have carried the shifting pin 28 from its position shown in Fig. 1 across to its position shown in Fig. 4 and with the push button 7 still depressed to hold the sash 6, the gripping device 14 and the finger 12 pressed inward, as previously described, such pin will then rest adjacent the diagonally disposed face 37' on said gripping device. When the push-button 7 is released it will permit the spring 15 to force the sash 6 outwardly to its normal position and with it said button, and such movement carries the face 37' on the gripping device 14 into sliding engagement with the rigidly locked shifting pin 28 in such a manner as to shift the said device from its position shown in Fig. 1 to its opposite position, as shown in Fig. 5, which position is that assumed by said device when the switch is at rest in its open position. Whether the contact blades 19 and 22 are thrown to their open or closed positions, in either case they are securely locked in such positions by the finger 12 when carried outward by the sash 6 in a manner to enter either of the slots 29 or 38 of the tumbler 21, as the case may be, and upon the release of the push-button 7.

To insure the requisite amount of tilt to the device 14 to bring the claw 27 on said device into proper and definite position with respect to the spring 25 and to render a positive engagement with and accurate operation of the same, the swing of the extremity 39 on said device is arrested by contact with the lug 40 on the bottom of the push button 7, as in Figs. 1 and 4, and to similarly provide a positively accurate engagement of the claw 26 with the spring 25, the swing of the extremity 41 on the said device is likewise arrested by contact with said lug, as in Fig. 5.

Assuming that the switch contacts are closed and that the contact clips 32 and 34 are connected with the source of supply, while the contacts 31 and 33 are meantime in connection with the appliances to be supplied, then a current will flow from supply clip 32, blade 19, and clip 31 to the appli- 120 125 130

ances and return to clip 33, thence through blade 22, clip 34 and back to supply.

When it is desired to operate the switch to close its contact the button 7 in the position shown in Fig. 1 is pressed in the usual manner, and thereby the sash 6, gripping device 14, and finger 12 are again carried inward, but in this instance said gripping device having been tilted over from its normal rest, as in Fig. 1, to its abnormal rest as in Fig. 5, the claw 26 on its inward travel will engage with and carry inwardly the projecting free end 25" of the spring 25, instead of claw 27 engaging and carrying inward the free end 24" of the spring 24, as occurred in the first named operation, as previously described, and this inward travel of the spring end 25" will cause a torsion upon the shaft 2, but in a direction tending to rock said shaft oppositely from the torsion exercised by the spring 24. When the sash 6 has reached its inward limit of movement, the finger 12 will have traveled rearward out of the slot 29 to the position shown in Fig. 4, while at the same time the segment 30 will escape said finger and permit the torsion of spring 25 to rock the shaft 2 in a manner to throw the tumbler 21 through a one-fourth revolution and in a direction to cause the stop-catch 35 to recede from said finger to carry the stop-catch 36 over to engage with said finger. By this movement the switch blades 19 and 22 are thrown through a quarter revolution, as from their open position shown in Fig. 5, to their closed positions, as shown in Fig. 1, and in the meantime the shifting pin 28 assumes its normal position, as shown in Figs. 1 and 2, in order to insure its sliding contact with the inclined face 37 on the gripping device 14, so that it will tilt said device over to its normal position of rest, as in Fig. 1, when the button 7 has been released to permit the outward return of the sash 6 to its normal rest.

The outer face of the button 7 is provided with a cross-mark 7' thereon, which is preferably formed by a suitable slot formed therein and filled with any suitable colored material to make a distinction between the same and the balance of said face, so that when the lug 40 on said button is engaged by either of the extremities 39 on the device 14 in the two side movements of the same it will act to turn said button a one-fourth revolution on its pin 8 carried by the sash 6, and thereby permit such mark to be placed in a vertical position for indicating when the switch is off, or in a horizontal position to indicate that the switch is on, as shown by Figs. 6, 7, 8 and 9.

If desired, the frame 4 can be provided with a threaded boss 42 on the front of the same and around the opening 10 for the button 7, so that the similar opening in the

face plate 4' can be threaded for engagement with said boss, and thereby permit said plate to be connected to said frame by such threaded connection, as shown in Fig. 5.

It will be observed that in the preceding description the preferred manner of operating the switch has been expressed, but it is desired not to restrict the same to the precise form of the various devices, but to anticipate that substantially the same equivalents within the fair scope of the invention may be employed therefor, while various modifications and changes in the design and operation of the various parts of my improved switch, other than those described, may be resorted to without departing from the spirit of the invention or sacrificing any of its advantages.

It will thus be seen that my improved switch can be applied to the single or multiple method of operating switches, of the quick-throw type, and will provide a switch of novel character at a limited cost, which will insure durability with an accurate and efficient operation, while such a switch provides for the use of a single push button having contact blades for being thrown in one direction into contact to close the circuit through the switch by a push on said button and by a similar and succeeding push of the same button the contact blades are thrown in a reverse direction and out of contact to open the circuit of the switch. It will also be seen that a flush construction is provided for by my improved switch and with a very shallow depth of switch to facilitate installation of the same, while such switch can be conveniently opened for the purpose of wiring or to expose the working parts of the same, or for the purpose of removing them for repairing or examination.

What I claim as my invention and desire to secure by Letters Patent is—

1. A switch of the character described, comprising a rocking shaft having contact blades mounted thereon, spiral springs on said shaft and connected to the same, a push-button mounted on a spring controlled guiding member, a gripping member pivoted to said guiding member and adapted to engage with said springs to rock said shaft and throw said blades, and means for releasing and limiting the movement of said blades.

2. A switch of the class described, comprising a rocking shaft having contact blades mounted thereon, spiral springs on said shaft and connected to the same, a push-button mounted on a spring controlled guiding member, a gripping member pivoted to said guiding member and adapted to engage with said springs to rock said shaft and throw said blades, and means for engaging with said gripping member to release and limit the movement of said blades.

3. A switch of the class described, comprising a rocking shaft having contact blades mounted thereon, spiral springs on said shaft and connected to the same, a push-button mounted on a spring controlled guiding member, a gripping member pivoted to said guiding member and adapted to engage with said springs to rock said shaft and throw said blades, and means mounted on said shaft for engaging with said gripping member to release and limit the movement of said blades.

4. A switch of the class described, comprising a rocking shaft having contact blades mounted thereon, spiral springs on said shaft and connected to the same, a push-button mounted on a spring controlled guiding member, a gripping member pivoted to said guiding member and adapted to engage with said springs to rock said shaft and throw said blades, a trigger finger on said gripping member, and means mounted on said shaft for engaging with said finger to release and limit the movement of said blades.

5. A switch of the class described, comprising a rocking shaft having contact blades mounted thereon, spiral springs on said shaft and connected to the same, a push-button mounted on a spring controlled guiding member, a gripping member pivoted to said guiding member and adapted to engage with said springs to rock said shaft and throw said blades, a trigger-finger on said gripping member, and a tumbler mounted on said shaft for engaging with said finger to release and limit the movement of said blades.

6. A switch of the class described, comprising a rocking shaft having contact blades mounted thereon, spiral springs on said shaft and connected to the same, a push-button mounted on a spring controlled guiding member, a gripping member pivoted to said guiding member and adapted to engage with said springs to rock said shaft and throw said blades, a trigger-finger on said gripping member, and a tumbler mounted on said shaft and having slots therein for engaging with said finger to release and limit the movement of said blades.

7. A switch of the class described, comprising a rocking shaft having contact blades thereon, two opposite disposed spiral springs on said shaft and connected to the same, a push-button mounted on a spring controlled guiding member, a gripping member pivoted to said guiding member and adapted to engage with one of said springs to rock said shaft and throw said blades, means for releasing and limiting the movement of said blades, and means for shifting said gripping member to engage the same with one of said springs.

8. A switch of the class described, comprising a rocking shaft having contact blades thereon, two opposite disposed spiral springs on said shaft and connected to the same, a push-button mounted on a spring controlled guiding member, a gripping member pivoted to said guiding member and adapted to engage with one of said springs to rock said shaft and throw said blades, a tumbler for engaging with said gripping member to release and limit the movement of said blades, and means on said tumbler for shifting said gripping member to engage the same with one of said springs.

9. A switch of the class described, comprising a rocking shaft having contact blades thereon, two opposite disposed spiral springs on said shaft and connected to the same, a push-button mounted on a spring controlled guiding member, a gripping member pivoted to said guiding member and adapted to engage with one of said springs to rock said shaft and throw said blades, a tumbler for engaging with said gripping member to release and limit the movement of said blades, and a pin on said tumbler and extending through said gripping member for shifting said member to engage the same with one of said springs.

10. A switch of the class described, comprising a rocking shaft having contact blades thereon, two opposite disposed spiral springs on said shaft and connected to the same, a push-button mounted on a spring controlled guiding member, a gripping member pivoted to said guiding member and adapted to engage with one of said springs to rock said shaft and throw said blades, a tumbler mounted on said shaft for engaging with said finger to release and limit the movement of said blades, and a pin on said tumbler and extending through said gripping member for shifting said member to engage the same with one of said springs.

11. A switch of the class described, comprising a rocking shaft having contact blades thereon, two opposite disposed spiral springs on said shaft and connected to the same, a push-button mounted on a spring controlled guiding member, a gripping member pivoted to said guiding member and adapted to engage with one of said springs to rock said shaft and throw said blades, a trigger-finger on said gripping member, a tumbler mounted on said shaft for engaging with said finger to release and limit the movement of said blades, and a pin on said tumbler and extending through said gripping member for shifting said member to engage the same with one of said springs.

12. A switch of the class described, comprising a rocking shaft having contact blades thereon, two opposite disposed spiral springs on said shaft and connected to the same, a push-button mounted on a spring controlled guiding member, a gripping member pivoted

to said guiding member and adapted to engage with one of said springs to rock said shaft and throw said blades, a trigger-finger on said gripping member, a tumbler mounted on said shaft and having slots therein for engaging with said finger to release and limit the movement of said blades, and a pin on said tumbler and extending through said gripping member for shifting said member

10 to engage the same with one of said springs.

13. A switch of the class described, comprising a rocking shaft having contact blades thereon, spiral springs on said shaft and connected thereto, a push-button mounted on 15 a guiding member, a gripping member pivoted to said guiding member and adapted to engage with said springs to rock said shaft and throw said blades, means for releasing and limiting the movement of said blades, 20 and spring means for returning said guiding member to its normal position when the button is released.

14. A switch of the class described, comprising a rocking shaft having contact blades 25 thereon, spiral springs on said shaft and connected thereto, a push-button mounted on

a guiding member, a gripping member pivoted to said guiding member and adapted to engage with said springs to rock said shaft and throw said blades, a trigger-finger on 30 said gripping member, means for engaging with said finger to release and limit the movement of said blades, and spring means for engaging with said finger to return said guiding member to its normal position when 35 the button is released.

15. In a switch, the combination of oscillating switch mechanism having projections, a reciprocating rocking gripping member having two arms each provided with a hook, 40 one for each of said projections, said hooks being turned toward each other, said hooks engaging with their corresponding projections alternately, said projections being located between said hooked arms and means 45 for reciprocating said gripping member.

In testimony whereof, I the said ADELBERT W. GRAY have hereunto set my hand.

ADELBERT W. GRAY.
